FOLDABLE IRONING TABLE

Filed Nov. 3, 1930

35 Inventor:
13 George W. Lewis.
by Wright Brown Trinity May

UNITED STATES PATENT OFFICE

GEORGE W. LEWIS, OF BERLIN, MASSACHUSETTS

FOLDABLE IRONING TABLE

Application filed November 3, 1930. Serial No. 493,039.

This invention relates to a foldable ironing table, comprising an ironing board and legs hinged thereto, the legs being crossed when the table is erected, and adapted to maintain the board in a horizontal position above a floor, and to swing relative to each other and to the board to erect and fold the table.

One object of the invention is to provide certain improvements in said legs whereby they are adapted to firmly support the board when the table is erected, and to laterally brace and support each other against strains tending to racking the erected structure and loosen the hinges connecting the supports with the board.

Another object is to provide improved confining means adapted to rigidly confine the table in an erected position.

Another object is to provide the board with hinges of improved construction.

Of the accompanying drawings forming a part of this specification,—

Figure 1 is a perspective view, showing an erected table embodying the invention.

Figure 2 is a fragmentary side view, showing the table conditioned as shown by Figure 1.

Figure 3 is a view similar to Figure 2, showing the table partly folded.

Figure 4 is a section on line 4—4 of Figures 1 and 2.

Figure 5 is an edge view, showing the table folded.

Figure 6 is a fragmentary sectional view on line 6—6 of Figure 2.

Figure 7 shows in perspective and partly in dotted lines one of the hinges described hereinafter.

Figure 8 shows in section a portion of one of said hinges and a portion of the board.

The same reference characters indicate the same parts in all of the figures.

The table includes an oblong ironing board 12, a wide leg hinged to the mid-length portion of the board, and a narrow leg hinged to an end portion of the board, said legs being crossed when the table is erected, and adapted to bear at a plurality of points on a floor. The wide leg includes two spaced

apart longitudinal members 13, hinged at their upper ends to the mid-length portion of the board, the outer ends of said members being adapted to bear at two spaced apart points on a floor. The wide leg preferably includes also a transverse holding bar 18, fixed to the outer end portions of said members, and two longitudinal bracing and confining bars 19, fixed to the outer members 13, and to the holding bar 18. Said confining bars are oppositely inclined and converge from the members 13 to the holding bar 18, and are separated from each other by a tapering space, as best shown in Figure 4, so that they are adapted to prevent lateral movements of the narrow leg, as hereinafter described.

The narrow leg is preferably wedge-shaped and includes two longitudinal members 21, hinged at their spaced apart inner ends to the outer or forward end portion of the board 12, the members 21 converging to their outer ends, which are connected by a fastener 24, and are adapted to bear on a floor.

When the table is erected, the narrow leg extends between the longitudinal members 13 of the wide leg, as shown by Figures 1 and 4, and its converging outer sides are in wedging contact with the converging inner sides of the confining members 19, so that the wedge-shaped narrow leg is wedged in the tapering space between the confining members, as best shown by Figure 4.

The wedging contact of the wide and narrow legs with each other causes each leg to laterally brace the other, and prevents any racking of the erected structure which might tend to loosen the hinge connections.

When the table is being adjusted to the folded position shown by Figure 5, the converging sides of the wide leg members 21 are withdrawn from wedging contact with the confining members 19.

The confining bars 19 and the holding bar 18 impart rigidity to the wide leg.

The table is provided with confining means resisting downward pressure exerted on the board and preventing folding movements of the legs when the table is erected. Said confining means includes cross-bars 16 and 17, 100

fixed to and extending between the longitudinal members 13 of the wide leg at diagonally opposite edge portions of said members, dowels 25 fixed to the narrow leg members 21 and projecting laterally in opposite directions therefrom, and a brace 26 hinged at one end to the board 12 and provided at its free end with a notch forming an abutment shoulder 28 and a stop shoulder 29.

10 The arrangement is such that when the table is erected and the lower edge of the cross-bar 16 bears on the upper edges of the narrow leg members 21, said leg members bear on the upper edge of the cross-bar 17, the dowels 25 bear on the forward edges of the wide leg members 13 and the abutment shoulder 28 of the brace bears on the upper edge of the cross-bar 16, the stop shoulder 29 engaging the bar 16 to hold the abutment shoulder in its operative position.

15 It will now be seen that the legs and board are rigidly connected when the table is erected, so that the board is adapted to support downward pressure exerted on any part thereof.

20 To permit the folding of the table, the brace 26 is disengaged from the cross-bar 16 as indicated by Figure 3, and the legs are folded against the board as indicated by Figure 5. 25 During the folding operation the brace 26 is confined against the board 12 as shown by Figure 5, by a transverse rod or striker 30 fixed to and extending between the narrow leg members 21.

30 Each of the hinges connecting the wide and narrow leg members and the brace 26 with the board is preferably constructed as best shown by Figures 7 and 8, which show the hinge connecting one of the wide leg members 13 with the board 12.

35 Each hinge includes a single piece of sheet metal bent to form a neck 31 and a pair of ears 32. The neck bears on the under side of the board 12 and has an orifice 33 receiving a rivet 34 which attaches the hinge to the board as shown by Figure 8. The ears 32 are provided with orifices 35 receiving a pintle member 36.

40 The ears 32 are flexible so that the ears of the hinges connecting the leg members 13 with the board may be inclined relative to the neck portion as shown by Figure 4, to conform to the inclination of said leg members. Said ears need not be thus inclined in the 45 hinges which connect the leg members 21 and the brace 26 with the board.

I claim:

1. A foldable ironing table, comprising a board, a wide leg, and a narrow leg, said legs being crossed when the table is erected and adapted to swing relative to each other and to the board to erect and fold the table, the wide leg including two spaced apart longitudinal members, hinged at their inner ends 50 to the midlength portion of the board and

having outer ends adapted to bear at spaced apart points on a floor, a transverse holding bar fixed to the outer end portions of said members, and inclined confining bars fixed to the longitudinal members and to the holding bar, and oppositely inclined so that they form opposite sides of a tapering space, the narrow leg being V-shaped and including two longitudinal members spaced apart and hinged to the forward end portion of the board at their inner ends and converging therefrom to their outer ends to bear on a floor and constitute a wedge which extends between and is in wedging contact with the inclined confining bars of the wide leg when the table is erected, so that the legs laterally brace each other, the table being provided with confining means resisting downward pressure on the board and preventing folding movements of the legs when the table is erected.

2. A foldable ironing table, comprising a board, a wide leg, and a narrow leg, said legs being crossed when the table is erected and adapted to swing relative to each other and to the floor, the wide leg including longitudinal members hinged at their inner ends to the midlength portion of the board, and having outer ends adapted to bear on a floor, the narrow leg including two longitudinal members hinged at their inner ends to the forward end portion of the board and having outer ends adapted to bear on a floor, cross bars fixed to and extending between

55 the longitudinal members of the wide leg at diagonally opposite edge portions of said members, dowels fixed to the members of the narrow leg and projecting laterally therefrom in opposite directions, to bear on the members of the wide leg when the table is erected, and a brace hinged to the board and provided at its free end with an abutment shoulder and a stop shoulder adapted to cooperate as described, with one of said cross bars when the table is erected, the narrow leg being provided with a striker adapted to confine said brace against the board when the table is folded.

In testimony whereof I have affixed my signature.

GEORGE W. LEWIS.
